DISCHARGE TUBE DISPLAY

Filed March 30, 1931

FIG 1.

FIG 2.

INVENTOR

Fred Hotchner

UNITED STATES PATENT OFFICE

FRED HOTCHNER, OF LOS ANGELES, CALIFORNIA

DISCHARGE TUBE DISPLAY

Original application filed May 25, 1929, Serial No. 366,069. Divided and this application filed March 30, 1931. Serial No. 526,344.

My invention relates to discharge tube display devices and more particularly to devices of this nature which are so constructed that the legend or message or display thereon may be varied at will by the owner of the sign as distinguished from the manufacturer thereof.

This application is a divisional application of my Patent No. 1,803,706, issued May 5, 1931. In my said prior patent I disclose a device of this general character in which the luminescence obtained from a gaseous conduction sign and in which the light emanates from said gaseous conduction tube in addition to being visible to display the tube, also illuminates a certain light reflecting display pattern such as letters or insignia so that these letters or insignia are also visible as part of the display.

This present application concerns itself more particularly with a device in which those portions of the display which receive their illumination from the gaseous conduction sign are of such a character that they may be readily changed by the owner of the sign as distinguished from the manufacturer.

Other objects of my invention will be apparent from a description of two specific forms thereof which follows in connection with the accompanying drawings, in which—

Fig. 1 is a display device partly in section of one form of carrying out my invention; and

Fig. 2 is a perspective view of a modified form thereof.

In the form of the invention as illustrated in my said prior application, I have utilized two plates of glass placed rather closely together in cooperative relationship with a gaseous conduction tube so arranged that it in itself is visible, and at the same time directs light rays toward other portions of the sign through the agency of the glass plates which reflect the light toward these other portions of the visible display. There are many forms of bringing this about, some of which are shown in my said prior application, but I am not adding those illustrations to this application, but am showing two forms which are illustrative in general of my invention, the principal features thereof being a gase-

ous conduction tube, a reflecting glass plate, and a surface illuminated by the gaseous conduction plate essentially through reflection upon which any suitable legends, insignia, or the like may be drawn or otherwise applied by the owner of the sign and changed at will.

In the form of the invention shown in Fig. 1, a sign is provided for show window mounting. It is constructed with a single sheet of glass 44 to which the tube 45 is mounted by means of suitable posts 46. The window 47 through which the sign is to be displayed is utilized in the place of a second glass plate such as used in other forms of my invention. A portion of the light emanating from the tube 45 is reflected into the space between the two glass plates by the rear surface of the window 47 and the front surface of the plate 44.

In the form of the invention shown, the central portion of the glass plate 44 is not provided with tubing and is designed for the receiving of any suitable display, such as advertising copy which may be written on the glass with any medium which will reflect or disperse the light or otherwise render such display luminous.

The object of this is to provide a suitable place for the provision of such copy which may be quickly removed and replaced by other copy. It is to be understood that if desired, raised letters may here be used which are suitably fastened in place between the plates. The complete sign thus serves as an announcement sign which may be quickly changed. It is detachable from the supporting cords 48 and 49 at the hooks 50 and 51. The cords are insulated conductors and they depend from the terminals of the transformer 52 which is located out of the line of vision.

The sign is spaced from the window by means of the bumper posts 53, 54, 55 and 56. Connection is made to the terminals 57 and 58 by means of the conductors 59 and 60. To make changes in the sign, it is unhooked from the cords, thereby also breaking the electrical connection, and then taken to a convenient place, the old message washed off and new copy written in the space 61.

Another embodiment of the invention is

shown in Figure 7. The two glass plates 62 and 63 are supported apart and above the cabinet 64 by means of the cast brackets 65 and 66. Both glasses slide in slots in the brackets, indicated by 67, 67, etc., and may be conveniently removed for the purpose of writing messages on the surfaces of the glasses. It is to be understood that while I prefer to use the front surface of the rear glass, it is possible to use any surface at all for this purpose. The illumination is furnished by the ornamental border tube 68, the terminals 69 and 70 thereof extending through the bushings 71 and 72 into the cabinet within which is contained a transformer. The space for copy in this case is indicated by 73.

Various methods may be used for providing the light reflecting characters in this invention. Paint pigments or glass frosting may be used. Water colors which may be readily washed off are also suitable. Then again letters or characters may be suitably pasted in place if desired.

From the description of two forms of my invention the same will readily be clear to those skilled in the art, and it will also be quite apparent that changes and modifications within the scope of the appended claims may be made without departing from its spirit.

Having, however, thus described two forms of my invention, what I claim as new and desire to secure by Letters Patent is:

1. A display sign of the character described having a pair of parallelly arranged light reflecting plates, a gaseous conduction light emitting display pattern forming part of the visible display and positioned between the planes of said plates in such manner as to leave certain portions of the visible display area unoccupied, and readily removable and replaceable light reflecting display characters also forming part of the visible display arranged in said unoccupied display area.

2. A display sign of the character described having a pair of parallelly arranged light reflecting plates, a gaseous conduction light emitting display pattern forming part of the visible display and positioned between the planes of said plates in such manner as to leave certain portions of the visible display area unoccupied, and readily removable and replaceable light reflecting display characters also forming part of the visible display carried by said plates and arranged in said unoccupied display area.

3. A display sign of the character described having a pair of parallelly arranged light reflecting plates, a gaseous conduction light emitting display pattern forming part of the visible display and positioned between the planes of said plates in such manner as to leave certain portions of the visible display area unoccupied, and readily removable and replaceable light reflecting display characters also forming part of the visible display

arranged in said unoccupied display area, a surface of each of said plates aiding by reflection to direct light from said light emitting display pattern to said light reflecting display characters.

4. A display sign of the character described having a pair of parallelly arranged light reflecting plates, a gaseous conduction light emitting display pattern forming part of the visible display lying adjacent the edges of said plates in such manner as to leave certain portions of the visible display area unoccupied, and readily removable and replaceable light reflecting display characters also forming part of the visible display carried by said plates and arranged in said unoccupied display area, a surface of each of said plates aiding by reflection to direct light from said light emitting display pattern to said light reflecting display characters.

5. A display sign of the character described having a light reflecting plate, a gaseous conduction light emitting display pattern forming part of the visible display lying closely adjacent said plate in such manner as to leave certain portions of the visible display area unoccupied, readily removable and replaceable light reflecting display characters also forming part of the visible display arranged in said unoccupied display area, and means for removably holding said plate in position, said means also serving as current conducting means.

6. In an electric display, a pair of extended spaced sheets of light transmitting material, means to hold said sheets of material together and in spaced relationship, an ornamental tubular light between said sheets of material and exposed to view through at least one of said sheets, one of said sheets being readily removable for the purpose of writing a message on a surface thereof.

7. A display device comprising a structure having substantially parallelly disposed reflecting surfaces, means to radiate light rays between said surfaces whereby a material portion of said rays are reflected back and forth between said surfaces, and readily removable characters of a substance capable of dispersing said light rays on one of said surfaces whereby said characters become apparently luminous by virtue of light rays escaping from said structure through said substance.

8. A display device comprising a structure having substantially parallelly disposed reflecting surfaces, a luminous gaseous conduction device to radiate light rays between said surfaces whereby a material portion of said rays are reflected back and forth between said surfaces, and readily removable characters of a substance capable of dispersing said light rays on one of said surfaces whereby said characters become apparently luminous by virtue of light rays escaping from said structure through said substance.

9. A display device comprising a structure having substantially parallelly disposed reflecting surfaces, a light source adjacent the edge of said structure and between the planes of said surfaces to radiate light rays between said surfaces whereby a material portion of said rays are reflected back and forth between said surfaces, and readily removable characters of a substance capable of dispersing said light rays on one of said surfaces whereby said characters become apparently luminous by virtue of light rays escaping from said structure through said substance.

10 In witness whereof, I hereunto subscribe
15 my name this 26th day of March A. D. 1931.

FRED HOTCHNER.
